TRUSSED RAFTER

Fayette Elam Marsh, 1025 N. Lincoln Street,
Hastings, Nebr.

Filed Apr. 20, 1955, Ser. No. 502,599

3 Claims. (Cl. 108—23)

This invention relates to a trussed rafter and more particularly with one fabricated of wood and adapted to be folded into a relatively small area to facilitate easy handling and shipment.

In the building trade there is an increasing appreciation of the many advantages of the trussed rafter for the roof structure, particularly in the smaller frame buildings, such as an individual residence or farm buildings.

However, one of the disadvantages encountered in this type of rafter is the fact that they land themselves most economically to mass production in a centrally located factory, but they are extremely hard to handle and expensive to ship, particularly if any great distance is involved.

There are two ways in which the manufacture or assembly of trussed rafters are traditionally handled. One, of course, is the previously mentioned factory assembly and shipment as a complete unit. Another method has been to precut the various sections and provide the builder with the jig, which might be used on the building site to guide the construction workers in the assembly of the unit.

The last method, while overcoming the objection of bulk, which is the disadvantage encountered in shipment, places an extra burden upon the builder and reduces the advantages of mass production and the consequent economy.

It is therefore an object of my invention to provide a trussed rafter which may be mass produced in a centrally located factory, and yet shipped in small, compact bundles to the building site where it will be finally connected.

It is yet another object of my invention to provide a trussed rafter which employs a plurality of pivotal joints.

It is a still further object of my invention to provide a device of the type described in which provision is made for bracing members adapted to provide a small margin of adjustment.

Still another object of my invention is to provide a trussed rafter in which the lower chord may be spliced at the building site while the balance of the rafter is already connected.

Other and further features and objects of the invention will be more apparent to those skilled in the art upon a consideration of the accompanying drawings and following specifications, wherein is disclosed a single exemplary embodiment of the invention, with the understanding, however, that such changes may be made therein as fall within the scope of the appended claims, without departing from the spirit of the invention.

In said drawings:

Figure 1 is a side view of a trussed rafter constructed according to my invention and fully assembled.

Figure 2 is a top view of a portion of the lower chord.

Figure 3 is a top view of a portion of the upper chord.

Figure 4 is an enlarged cross sectional view of a pivotal joint of the rafter shown in Figure 1. The view is taken at section line 4—4.

2

Figure 5 is a side view of the rafter, partially folded and disconnected at points provided for that purpose.

Figure 6 is a view in perspective of the crown plate showing the pivotal point within the plate in dotted lines.

5 Figure 7 is a view in perspective of the splicing saddle in enlarged view, and

Figure 8 is a side view of the diagonal brace used for adjustment in the fully assembled rafter.

Referring now to the drawings, and particularly to

10 Figure 1; a trussed rafter, constructed according to my invention, is comprised of the lower chord 10 and the two angular upper chord members 11 and 12. These outline the rafter. Two diagonal braces 13 and 14 are pivotally connected to the crown block 15 and extend downwardly and outwardly to connect to the lower chord 10 by means of bolts 16 and 17. Two additional diagonal braces 18 and 19 are nailed in an outward position to the previously mentioned diagonal braces 13 and 14, and extend to the upper chord where they are nailed in 20 position.

The lower chord consists of two sections 20 and 21. These are separate, but are spliced together at their joining points by the steel saddle member 31.

25 The upper and lower chords are connected at their outer extremities by bolts 22 and 23. The inner ends of the upper chords 11 and 12 are connected to the crown plate by bolts 24 and 25.

It is appropriate to indicate here that the lower chord

30 10 is formed of a single thickness of timber, while the upper chords 11 and 12 are formed of two spaced-apart planks, such as 26 and 27 of Figure 3.

35 While an ordinary bolt connection could be used at joints 22, 23, 24 and 25, I prefer to use ring connectors as well as bolts, such as are shown at 28 and 29 of Figure 4. It will be noted that these are positioned between two adjoining planks in a recess cut for that purpose. Of course the pivotal movement of two boards so connected is much easier and, at the same time, the loading is distributed over a wider area; therefore

40 the strength of the joint is increased.

Referring now to Figure 5; it will be seen that a rafter constructed according to my invention is capable of being folded, using the crown plate 15 as the pivot point around which the entire motion of the various parts is centered.

45 The two lower chords, such as 21, being pivotally mounted on the bolt 23, and comprising only one thickness of lumber, can be folded upwardly between the two planks of the upper chord. The brace 13, which is also pivotally mounted on the crown plate, may be folded 50 inwardly and will lie along the edge of the folded upper and lower chords. This makes a complete folded assembly, such as is shown generally at 30. These two halves may then be brought together to make one small bundle.

55 The diagonal braces 18 and 19 may be packaged separately as well as the saddle member 31.

The diagonal braces are not incorporated in the structure by a pivotal joint for a particular reason. It is a well known fact that in cutting lumber, there should be a fairly large permissible tolerance. As a result, the truss, when fully assembled, may not be quite as rigid or in the exact form as would be desired. These two short braces can then be nailed into position, providing thereby a form of adjustment and giving absolute rigidity to the entire structure.

65 It will be noted that the saddle member serves as a splice means for the two lower chords and have a number of nailing holes. The use of the plurality of nailing holes provided gives the joint considerable rigidity and strength, which in turn is imparted to the entire structure.

70 It will be seen, from the foregoing description, that I

have provided a trussed rafter which may be factory assembled, and when delivered to the building site, will require very little additional work. It need only be opened up to its full extent, the splice member placed in position and nailed to the lower chord, the two diagonal braces nailed in position, and the various bolts tightened. The rafter is then ready for erection.

Of course it is obvious that many more of these packaged trusses can be shipped in a single truck or freight car than could be shipped were they fully assembled and nailed together, as is the conventional practice. It is also apparent that they are much easier to assemble on the building site and much more accurate than they would be were they comprised of simply precut lengths of lumber.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In a foldable trussed rafter of the type described, a substantially rectangular crown plate comprising a single thickness of material, a pair of upper chord members pivotally attached to said crown plate and rotatable inwardly and outwardly from each other, said chord members each comprising a pair of planks positioned one on each side of said crown plate, the pivotal mounting points of said chord members being spaced apart on centers substantially twice the width of one of said chord members, a pair of brace members pivotally mounted on said crown plate at a point below and midway of the aforesaid pivotal mounting position of said chord members, said brace members being positioned one to each side of said crown plate and of a width not greater than the width of one of said chord planks to permit said brace members to lie therebetween and parallel thereto in the same plane as the adjacent planks of the adjacent chord members; a lower chord member comprising a co-linear plank in two sections, each section thereof being pivotally joined at an end of each to the outer end of said respective upper chord members and being of a lesser length than said upper chord members, each section of said lower chord member being positioned to be folded coextensive with and in between the opposed planks of said upper chord members, and splice means for connecting the two sections of said lower chord member, the positioning of said upper and lower chord members and brace members as aforesaid being such that when folded, the pairs of planks forming the upper chord members and brace members on either face of the crown plate will lie in substantially the same plane parallel to each other and the sections lower chord member will lie between the separate planks of their respective upper chord member and in substantially the plane of the single thickness of the crown plate.

2. In a device of the type described, a crown plate, upper right and left chord members, each comprising a pair of spaced-apart planks positioned on either side of said crown plate and pivotally attached thereto in spaced relation to permit them to be pivoted inwardly to a spaced apart and parallel position thereby leaving a measured space therebetween, a lower chord member comprising a co-linear plank in two sections, each section thereof being pivotally joined to the outer end of said upper chord members and between said planks thereof, each section of the lower chord member being of slightly lesser length than the adjacent upper chord member,

whereby said sections of the lower chord member may be folded into said respective upper chord members, and brace means pivotally attached respectively against front and rear faces of said crown plate between the pivoted attachments of said upper chord members thereto and adapted to be secured to said lower chord member, said pivotally mounted brace means being so positioned that they may be folded into position to occupy said measured space between said pivoted upper right and left chord members, and splice means for joining the free ends of said two sections of co-linear plank constituting the lower chord member.

3. An article of manufacture of the type described comprising in combination an elongated crown plate of generally rectangular shape and of a thickness from front to back of substantially less than its length or height, a pair of right hand chord members attached pivotally at one end to one end of the crown plate and disposed one against the front and one against the back of said crown plate, a pair of left hand chord members attached pivotally at one end to the other end of the crown plate and likewise disposed one against the front and one against the back of said crown plate, said right and left hand pairs of chord members extending parallel to each other and being spaced apart in their pivotal connections to said crown plate so as to leave a measured space therebetween said parallel extending chord members, a right hand lower chord member of lesser length than the right hand chord members and pivotally connected at one end to the other end of said right hand chord members and lying sandwiched therebetween and of substantially the same width as said right hand chord members, a left hand lower chord member of lesser length than the left hand chord members and pivotally connected at one end to the other end of said left hand chord members and lying sandwiched therebetween and of substantially the same width as said left hand chord members, a first brace member having one end lying adjacent the front of said crown plate, a second brace member having one end lying adjacent the rear of said crown plate, a common pivot connecting said ends of the first and second brace members to the crown plate at a point lying between said pivotal connections of said right and left hand chord members to the crown plate and spaced from a line joining the pivotal connections of said right and left hand chord members in a direction toward the other ends of said right and left hand chord members, said brace members occupying throughout their length a portion of said measured space between said right and left hand chord members and being parallel to and each lying in a separate common plane with their respectively adjacent right and left hand chord members.
